UNITED STATES PATENT OFFICE

2,378,306

SHEET FEEDING MECHANISM

William F. Leonhart, Mount Lebanon, Pa., assignor, by mesne assignments, to Continental Can Company, Inc., New York, N. Y., a corporation of New York

Application April 12, 1943, Serial No. 482,721

7 Claims. (Cl. 271—32)

My invention relates to mechanism for withdrawing sheets singly and in rapid succession from a stack of the sheets and particularly to mechanism by which the sheets are releasably held at their edges while individual sheets are separated from the stack. An object of the invention is to provide an improved apparatus by which the stack of sheets is reliably held while individual sheets are withdrawn in a manner to insure a single sheet at a time being released and fed forward from the stack.

The United States Patent to Laxo, No. 2,235,377, March 18, 1941, Grain breaker, illustrates a grain breaking machine for processing metal sheets designed for use in the manufacture of can bodies, and discloses a mechanism for feeding and withdrawing the can body sheets singly and in succession from the bottom of a stack, and feeding them to the grain breaking mechanism. The present invention, as illustrated herein, is adapted for use with such a machine and embodies certain improvements on the mechanism shown in said patent, particularly the separators which engage the edges of the lowermost sheets in the stack.

Other objects of the invention will appear hereinafter.

Referring to the accompanying drawings:

Figure 1 is a sectional elevation of an apparatus embodying my invention.

Fig. 2 is a plan view showing the feeding hopper.

Fig. 3 is a fragmentary sectional elevation showing particularly a separator holder and fingers.

Fig. 4 is a view of a separator as indicated by the line 4—4 on Fig. 3.

Fig. 5 is a perspective view of the separator center finger.

Fig. 6 is a perspective view of the separator double finger.

Referring to the drawings, a stack 10 of flat sheets 11, as for example, metal sheets adapted for making can bodies, is supported in a feeding hopper or framework, including horizontal side members 12 (Fig. 2), cross bars 13 and 13^a, and vertical corner guides 14. The weight of the stack is supported by separator devices 15 mounted on the hopper frame.

The sheets 11 are withdrawn one by one from the bottom of the stack by means including suction cups 16. A suction line extending to the cups includes a pipe 17 which opens into a bearing sleeve 18 in which reciprocates a vertical tubular shaft 19. A crosshead 20 on the upper

end of the shaft 19 carries the vacuum cups 16. The shaft 19 is periodically reciprocated by means including a bell crank lever 21 connected through a link 22 to a head 23 attached to the lower end 5 of the shaft 19. When the shaft is lowered, carrying with it the vacuum cups 16, a sheet 11 is withdrawn from the stack and disposed on supporting bars 24. The suction line is cut off and the vacuum released just before the sheet is placed on the plates 24. The sheet is immediately fed forward to the grain breaker mechanism 25 by means of a kicker arm 26 in the form of a bell crank fulcrumed on a pivot 27 and connected through a link 29 to the head 23.

Reference may be had to the above mentioned Patent 2,235,377, for a more detailed disclosure of the construction and operation of the parts above described.

The sheet separators 15, embodying features of 20 novelty comprised in the present invention will now be described:

The separators 15 which are mounted on the side bars 12 of the hopper, each comprises a holder 35 adjustable along the bar 12 and held 25 in position by a face plate 36 and clamping screws 37. The bars 12 and holders 35 thereon, are adjusted to provide a narrow space between the holder and the edges of the stack. A recess 38 is formed in the face of the holder to receive the 30 separator fingers. These include a separator center finger 39 and a double separator finger 40. These fingers are pivotally mounted on a hinge rod 41 secured in the holder 35. The double finger 40 is in the form of a yoke comprising 35 parallel-spaced arms connected by an integral web 42, the finger 39 being mounted between said arms.

The fingers are adjustably held in position 40 to engage the sheets 11 adjacent the lower ends of the stack, by means of upper and lower adjusting screws 43 and 44 (Fig. 3), which respectively engage the center finger 39 and the web 42 of the double finger. The finger 39 has a smooth front face 45 which is downwardly and inwardly inclined, so that the lower portion of said face engages the edges of the lower sheets 11 of the stack.

The lower portions of the front faces of the 45 double fingers 40 are formed each with a series of minute teeth or ribs extending thereacross and providing holding surfaces 46 to grip the lowermost sheets of the stack after said sheets have passed below or out of contact with the surfaces 45 of the middle fingers. The double fingers 40 are adjusted to bring said holding surfaces 46 in-

wardly a slight distance beyond the surfaces 45 of the center fingers. The double fingers are formed with their front faces 47 more or less concave or in the form of a re-entrant angle to permit the holding surfaces 45 of the center fingers to hold the sheets above the corrugated or saw tooth surfaces 46.

In operation, the weight of the stack 18 is supported mainly by the center fingers 38 and the sheets remain flat until they come in contact with the inclined surfaces 45 of the center fingers. Continued downward movement of the sheets causes them to bow downwardly. The amount of bowing gradually increases until the support of the sheets is transferred to the toothed surface 46. As the sheets move downward, the suction cups 16 reach up periodically and withdraw the lowermost sheet and pull it downward off the separator fingers. The operation of the suction cups gives a slight motion to several of the lowermost sheets of the pack. The toothed surfaces 46 operate by a scraping action to slightly separate the edges of the lowermost sheets and prevent more than one from being withdrawn from the stack at one time. When more than one sheet is initially pulled loose by the suction cups, the extra sheets remain supported at some point on the toothed surfaces until subsequent downward strokes of the suction cups withdraw them singly from the stack. It will be seen that the toothed fingers function chiefly to separate the sheets and to assure their being withdrawn and fed singly, while the weight of the stack or body of sheets is carried mainly by the smooth center fingers. As shown in Fig. 1, the end frame members 13 and 13^a are provided with recesses 38 in which separator fingers are mounted in position to engage the end edges of the sheets and operate in the same manner as the fingers mounted in the holders 35.

Modifications may be resorted to within the spirit and scope of my invention.

I claim:

1. The combination of means for holding a stack of flat sheets, means for withdrawing said sheets singly and in succession from one end of the stack in a direction perpendicular to the sheets, a holding device having a holding surface positioned and arranged to engage the edges of the sheets adjacent said end of the stack, said surface being inwardly inclined to project into the path of the sheets and cause them to be bowed as they approach the position to be withdrawn from the stack, a separator finger separate from said holding device and having a toothed surface positioned to engage said edges of the sheets as they move beyond said inclined surface and hold said edges separated to prevent more than one sheet at a time being withdrawn from the stack, and means for separately adjusting said holding device and said separator finger each toward and from the path of the sheets.

2. Sheet feeding mechanism comprising means for holding a stack of flat sheets, means for withdrawing said sheets singly and in succession from one end of the stack in a direction normal to said sheets, and separator devices positioned at opposite sides of the stack adjacent said end thereof, said devices comprising holding surfaces

forwardly and inwardly inclined relative to the direction in which the sheets are withdrawn, and spaced to cause the sheets to be bowed as they move along said surfaces, said separator devices including corrugated holding surfaces positioned beyond said inclined surfaces in the direction of movement of the sheets and in position to engage the edges of the sheets and hold them separated, and means for adjusting said corrugated surfaces relative to said holding surfaces in directions toward and from the sheets at said end of the stack.

3. Sheet feeding mechanism comprising a separator for separating the edges of the sheets in a stack and holding said edges while the sheets are withdrawn from the stack, said separator comprising a holder, a finger pivoted in said holder and having a sheet engaging surface, and a second finger pivoted in said holder and having a fine-toothed surface positioned adjacent to and extending beyond said first mentioned surface.

4. Sheet feeding mechanism comprising a separator for separating the edges of the sheets in a stack and holding said edges while the sheets are withdrawn from the stack, said separator comprising a holder, a center finger mounted in said holder and having a surface for engaging the edges of the sheets, and a double separator finger mounted in said holder and having toothed surfaces at opposite sides of said center finger, said toothed surfaces being positioned beyond said first mentioned surface in the direction of movement of the sheets.

5. A separator comprising a holder, a center finger, and a double finger, said fingers being pivoted in said holder to swing about the same axis, said double finger comprising a pair of arms between which said center finger is pivoted, said double finger having toothed surfaces.

6. In an apparatus for withdrawing sheets singly and in succession from the bottom of a stack of said sheets, a separator comprising a holder formed with a recess in one face thereof, a pivot rod mounted in the said recess, and separator fingers positioned within said recess and pivoted on said rod and depending therefrom, said fingers including a finger having a surface positioned and arranged to engage the edges of the lower sheets in said stack and forming a support for said sheets, and a second finger having a toothed surface extending below said supporting surface of the first finger.

7. In an apparatus for withdrawing sheets singly and in succession from the bottom of a stack of said sheets, a separator comprising a holder formed with a recess in one face thereof, a pivot rod mounted in the said recess, and separator fingers positioned within said recess and pivoted on said rod and depending therefrom, said separator fingers including a center finger and a double finger, the latter having spaced arms between which the center finger is mounted, said center finger having an inclined surface to engage the edges of the sheets in said stack, and said double finger having toothed sheet-engaging surfaces on opposite side of and below said inclined surface.

WILLIAM F. LEONHART.
